Primary Examiner — Cynthia R Underwood*(74) Attorney, Agent, or Firm* — Georgi Korobanov(57) **CLAIM**

The ornamental design for a tablet cover with keyboard, as shown and described.

DESCRIPTION

FIG. 1 is a front, top, and right side perspective view of a tablet cover with keyboard, showing my new design;

FIG. 2 is a rear, top and right side perspective view thereof;

FIG. 3 is a front, top, and right side perspective view in use state thereof;

FIG. 4 is a front, top, and right side perspective view in closed state thereof;

FIG. 5 is a front view thereof;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

The broken lines shown in the drawings illustrate portions of the tablet cover with keyboard that form no part of the claimed design.

1 Claim, 10 Drawing Sheets(56)
